REFLECTING DISPLAY

Abner F. Sacksteder, Chicago, Ill.

Application October 30, 1937, Serial No. 171,875

10 Claims. (Cl. 40—130)

This invention relates in general to a folding display of the reflecting surface type in which the surface is flat when folded and curved when distended at the back and spaced from letters or characters to provide a novel and distinctive appearance.

An important object of the invention is in the provision of a folding display of this type in which the desired curvature of the reflecting surface is automatically produced in setting up or distending the display.

A further object of the invention is to provide a display of this kind in which the letters or characters are changeable and are located at a distance from a portion of the reflecting surface so that the display is open at the top for illumination by light from the back, front or top.

A further object of the invention is in the provision of a collapsible and self-supporting display on which the backs of the letters or characters are spaced from the reflecting surface and may be colored the same or variously to produce different reflecting effects, depending upon the direction of the light which illuminates the display.

A still further object of the invention is in the provision of a colored display with a curved reflecting surface for receiving light from different angles and projecting the light forwardly through the letters or characters, giving the appearance of artificial or neon lamp illumination.

Other and further objects of the invention will appear hereinafter.

In the accompanying drawing illustrating preferred embodiments of the invention,

Fig. 1 is a perspective of a display set up or distended embodying principles of this invention;

Fig. 2 is a sectional view taken on the line 2—2 of Fig. 1;

Fig. 3 is a section taken on the line 3—3 of Fig. 2;

Fig. 4 is a sectional view of the display when collapsed; and

Fig. 5 illustrates a modified form of the invention as mounted upon a collapsible easel structure.

In providing a curved surface at the back of display letters or characters and in spacing the upper end of the surface from the backs of the letters, the top of the display is left open for the admission of light from all directions. This light striking the curved reflecting surface causes a reflection of the back of the letter upon the surface itself and provides a bright background, for the letters or characters so that they stand out clearly when viewed from the front, causing the display to have the appearance of an artificially or neon lamp illumination with only natural lighting. When the display is artificially illuminated, entirely different display effects are produced, depending upon the colors of the reflecting me-

dium, the backs of the letters as well as the front of the display.

Referring now more particularly to the drawing, a display composed of cardboard has a box base 6 for supporting it in upright position upon any plane surface with an upright back plate 7 and a front slot 8 for the changeable insertion of cut letters or characters 9 which have supporting base portions 9a inserted in the slot 8 at the front of the base and at a distance from the back plate 7.

Attached by an adhesive or any other suitable means at the upper end of the plate 7 is a reflecting sheet 10 preferably composed or faced with foil or foil paper 11 and preferably having 15 ribs 12 which extend transversely or horizontally, thereby producing an attractive novel reflecting background for the characters 9 which may be colored or plain, preferably as gold or silver foil, but reflecting paper of this kind being also made 20 in colors and having vertical ribs or grooves as well as the horizontal ones. The lower end of this reflecting material is free and unconnected but when the display is set up the lower end 13 abuts the top of the box base and upper end of a front 25 piece 14 or engages the back of the characters 9 at this point so that the lower free end of the reflecting material is curved in a predetermined manner, depending upon the length of the reflecting sheet. This curvature may be in the 30 arc of a circle, a parabolic or other curve, and the stiffness of the reflecting material is such that it maintains this curvature whenever the display is set up, the transverse ribs or grooves 12 aiding the curvature of the reflecting material.

The supporting box base has a top 15 and a bottom 16 and the ends 17 are formed with flaps 18 adapted to be inserted within the box base and engaged by an inwardly bent tongue 19 near the end of the base so that the base may be solidly set up and connected for supporting the display and reflecting portion in a proper manner. In order to assist in setting up the tongues 19 the base is also provided near each end with a finger opening 20.

When the structure is collapsed the base being in the form of a four-sided figure, will collapse flatly downward with respect to the plate 7 as soon as the locking flaps 18 are disengaged from the tongues 19 and the flaps 17 folded outwardly 50 in line with the front pieces. In this condition the lower free end of the reflecting material is loosely engaged between the backs of the characters 9 and the upper face of the box top 15 and in flat condition.

Various other displays embodying a curved reflector spaced from and at the back of changeable or die-cut letters and characters may be utilized to obtain the advantage of the open top illumination. In the structure shown by Fig. 5 60

a front display plate 21 has cut letters, characters or openings 22 which assist in forming the display. Attached to the back is a foldable easel 23 having a hinged locking wing 24 and at the upper end is a curved surface 25 for seating a reflector 26 of the foil or other suitable type as above described. This reflector may be attached at its lower end to the front plate by staples 27 or by an adhesive, it rests upon the curve surfaces 25 5 of the easel and at its upper end is attached by an adhesive or otherwise to the upper end of a plate 28 having perforations 29 adapted to be engaged by a tongue 30 projecting from the rear edge of each of the easel wings for holding the plate 28 in place. Thus when the easel is set up the plate 28 supports the reflecting surface of the rear of the openings 22 forming the letters or characters and causing illumination from the front, top and sides to be projected through the 10 openings forming the letters, as illustrated by the rays *a*, *b* and *c* from the front, back and top of the reflector as also illustrated in Fig. 2.

When light falls on the backs of the letters or characters, any different or distinctive coloring 15 on the back of the lettering is mirrored in the reflecting surface 11 as represented by the colored shadows *d* in Fig. 1. These colored shadows cause a distinctive appearance of the display, depending upon the coloring at the back of the letters 20 and also upon the coloring of the reflecting surface itself. Sometimes the shadows are mere fragments or blotches of color and at other times they are easily distinguished as shadows of the letters or characters in front of them. In any 25 event it suggests an artificially lighted display suggesting and more or less simulating a neon or other electric lamp illumination without requiring the actual lamp itself.

Displays of this kind may be set upon counters, 30 in show-windows, receiving illumination at the top from either the front or the back, causing the illumination of the back of the characters visible from the front as above explained, or if the illumination is directly from above, the curved 35 portion of the reflector will also cause the letters or characters to be illuminated and to stand out clearly as a display when seen from the front thereof.

I claim:

1. A display device of sheet material comprising 40 a back plate and a display character supported at a distance in front thereof, and a reflector extending from the back plate downwardly at a distance behind the character and turned forwardly at the bottom to the rear lower 45 exposed end of the character.

2. In a folding display formed of sheet material, a rear plate and a front character support spaced therefrom, a flexible reflector extending 50 to the rear plate in a curve upwardly from the support and spaced at the top from the back of a character held therein.

3. In a folding display formed of sheet material, a front character holder and a rear support 55 spaced therefrom, a flexible reflector extending in a curve upwardly from the holder to the support, the reflector having means for attaching it to the display at one end and being loose at the other so that it will extend flatly between the holder and the support when the display is collapsed.

4. An advertising device formed of sheet material and foldable to form a box base with a support at the rear and with a slot at the front

for inserting changeable letters or characters of sheet material, and a flexible reflector attached to the support and free at its lower end and of such a length that the lower end of the reflector will engage the front of the box base at the rear of the character holding slot for setting up the reflecting surface in a curve of predetermined design for reflecting light from all directions through the letters or characters at the front of the base. 5

5. A display sign comprising a supporting base, an open letter, character or symbol supported in upright position by the base, and a curved reflecting surface extending upwardly and rearwardly from the rear of the base of the letters or characters, the top being open between the reflecting surface and the upper ends of the letters or characters to permit light to enter between them from the front, sides, top and back. 10

6. In a folding display sign made of sheet material, a box base having inwardly foldable end flaps to hold it in rectangular supporting position, a plurality of letters or characters, means forming a slot at the front of the base into which the letters or characters are interchangeably inserted, a supporting plate at the rear of the base, and a reflector of flexible material attached to the upper end of the plate and loose at the lower end, the length of the reflector being such that it is engaged by the top of the base and said means 15 and curved rearwardly at the back of the letters or characters when the box base is set up in extended position. 20

7. In a display sign, a supporting base, a plurality of open characters made of sheet material supported at the front of the base having colored backs, a reflecting surface curved upwardly and rearwardly from the lower ends of the characters, means extending upwardly from the base for supporting the upper end of the reflecting surface, the reflection from the backs of the letters or characters appearing on said curved surface and being visible between the letters or characters from the front of the display. 25

8. A folding display made of sheet material 30 comprising a base for supporting apertured or die-cut characters or symbols at the front thereof, means forming a flexible reflector, a support in connection with the base for one end of the reflector, the other end being loose and held in 35 curved position at the back of the letter or symbol in an upwardly and rearwardly curved position open at the top and ends so that the curved surface will pick up light from many angles observable through the letters or characters from 40 the front thereof. 45

9. A display device in accordance with claim 8 45 in which the surface of the reflector is grooved or embossed to assist in reflecting light from various angles due to the curvature and embossing 50 thereof.

10. A foldable display device comprising front die-cut or open letters or characters, an extensible base for supporting the letters or characters, means forming a flexible reflector attached to the 55 support at one end and loose at the other, the base engaging the reflector to curve it upwardly and rearwardly at the back of the die-cut letters or symbols whereby the reflector extends flatly between the base and the letters when the display 60 is collapsed or folded and automatically assumes a predetermined curvature when the display is extended or set up. 65

ABNER F. SACKSTEDER.
